UNITED STATES PATENT OFFICE.

EARL J. WHITTAKER, OF NEAR TUMWATER, WASHINGTON.

LOG-TURNER.

1,047,599.

Specification of Letters Patent.

Patented Dec. 17, 1912.

Application filed March 9, 1911. Serial No. 613,315.

To all whom it may concern:

Be it known that I, EARL J. WHITTAKER, a citizen of the United States, residing near Tumwater, in the county of Thurston, State 5 of Washington, have invented a new and useful Improvement in Log-Turners, of which the following is a specification.

This invention relates to log turners and especially to steam operated log turners for 10 use in saw mills whereby a log of any size lying on the saw carriage may be turned so as to present a different face to the saw, and has for its objects to provide a device which will accomplish this aim with great speed 15 and ease.

Further objects of my invention are to make a device which can be mounted on the steam niggers at present in use and which will greatly improve their action as will appear in the further description of the 20 machine.

I attain these and other objects by the devices, mechanisms and arrangements illustrated in the accompanying drawings in 25 which—

Figure 1 is an elevation showing my invention withdrawn below the mill platform and ready to be operated; Fig. 2 is a similar view showing it engaging the log and ready 30 to turn it outward on the carriage; Fig. 3 is an enlarged view of a portion thereof with the log hook withdrawn from operative position; and Fig. 4 is a similar view showing the log hook in operative position.

Similar numerals of reference refer to 35 similar parts throughout the several views.

The vertical steam cylinder 1 is mounted below the floor of the mill substantially in the saw line thereof and is provided with a 40 suitable piston acting therein in the usual manner, said piston having a piston rod 3 passing through the upper head of the cylinder 1. A cross head 4 is secured to the end of the piston rod 3 and slides vertically in 45 the guides 5 secured to the frame work of the mill. The main bar 6 of this device is pivotally secured at its lower end to the cross head 4 and extends upward therefrom, but has a controlled movement on the said 50 pivotal connection so that it can travel either directly upward or radially about said pivot. The said bar 6 has an enlargement 7 at its upper end and a spur tooth 8 is secured near the upper end thereof in the usual 55 manner. The spur tooth 8 projects from the part 7 toward the log and is adapted to act

on said log only during its upward motion. A pivoted steam cylinder 9 is supported below the mill floor and is provided with a piston and piston rod 11 similar to the above 60 described piston and piston rod, the outer end of piston rod being pivotally secured to the said enlargement 7 of the bar 6. Both of the cylinders 1 and 9 are substantially the same as those at present in use and are controlled by similar means, said means forming no part of this invention and therefore not being further mentioned. 65

A bracket 12 is secured to the lower end of the bar 6 and extends outward therefrom 70 and carries a short cylinder 13, pivotally mounted near its end, said cylinder having a piston 14 therein with a long piston rod 15 extending therefrom. A log hook 16, is pivotally secured at a suitable point to the 75 upper part of the bar 6, the piston rod 15 being secured thereto on the other side of the pivot thereof. Steam is conveyed to each end of the cylinder 13 by means of two flexible steam pipes 17, the steam therein 80 being controlled by any suitable means. The position of the said log hook 16 relatively to the bar 6 is therefore controlled by the position of the piston 14 within the cylinder 13. 85

This improved log turning bar operates in the following manner:—When steam is admitted to the under side of the cylinder 1 the piston thereof is forced upward and carries the bar 6 upward with it. Simultaneously 90 steam may be admitted to the front end of the cylinder 9 drawing the piston backward, said piston drawing the said bar 6 backward by means of the piston rod 11. The bar 6 now occupies the raised and inclined position with the hook 16 lying beside the said bar 6. If, however, the steam is admitted to the top end of the cylinder 13 the piston 14 thereof is forced downward and the rod 15 turns the hook 16 on its pivot, raising its 95 sharpened end so that it extends in front of the bar 6. Steam is now admitted to the rear end of the cylinder 9 forcing the piston thereof forward and with it the upper end of the bar 6 until said bar occupies the vertical position. Steam is now admitted to the lower end of the cylinder 13 thus forcing the piston 14 upward and swinging the hook 16 downward bringing it into the log. The operator now reverses the movement of the piston rod 11 of the cylinder 9 causing the 100 bar 6 to move backward thus rolling the log 105

on the head block away from the knee of the carriage. Then the log hook is swung into its inoperative position. Then the motion of said piston rod 11 is again reversed 5 and the log is pushed back on the carriage and against the knees. The bar 6 may be brought back to its initial position by reversing the steam in the cylinder 1. To turn the log away from the bar the spur tooth 8 10 engages the log on the upward motion of the bar 6 and turns it on the head blocks and against the knees.

Having described my invention what I claim is:—

- 15 In a log turner, the combination with a fixed vertical guide track; of a cross-head engaging said guide track and free to move vertically thereon; a fixed vertical steam cylinder; a piston rod, with piston in said cylinder, operated by the steam therein and engaging said cross-head to move it vertically on said guide track; a bar, pivoted at

its foot to said cross-head; a pivoted cylinder acting at an angle to said first cylinder; 25 a piston rod, with piston in said cylinder, operated by the steam therein and engaging the head of said bar whereby the distance of said bar head from the pivot center of said second cylinder is controlled; a hook pivoted to said bar head and adapted to lie to the 30 rear of the face thereof when in inoperative position but to extend over the log when in operative position; a bracket extending out from the foot of said bar; a third steam cylinder mounted on said bracket; and a 35 piston rod, with piston in said third steam cylinder, operated by the steam therein and engaging the end of said hook, whereby said hook is swung on its pivot out from said bar to engage the log.

EARL J. WHITTAKER.
